UNITED STATES PATENT OFFICE.

CHARLES E. BENHAM, OF SCHENECTADY, NEW YORK.

KEYBOARD FOR COMPOSING-MACHINES.

1,106,538.

Specification of Letters Patent. Patented Aug. 11, 1914.

Application filed February 7, 1914. Serial No. 817,185.

To all whom it may concern:

Be it known that I, CHARLES E. BENHAM, a citizen of the United States, residing at Schenectady, county of Schenectady, State 5 of New York, have invented certain new and useful Improvements in Keyboards for Composing-Machines, of which the following is a specification.

The present invention relates to key 10 boards of so-called composing machines and in particular to key boards of machines of the Lanston monotype system although it is not necessarily limited thereto. I shall, however, describe my invention with reference 15 to such machines because it is particularly applicable thereto.

The ordinary key board in its operation requires that the operator shall depress and release a key each time its corresponding 20 character is to be reproduced. In my Patent No. 1,099,734, issued June 9, 1914, I have described and claimed an improved key board arrangement whereby any desired character can be reproduced indefinitely 25 so long as the key is held in its depressed position by the operator. When the key is released the automatic reproduction of the character ceases and the operator proceeds in the usual manner. Such an arrangement on account of its high speed of 30 operation requires close attention and considerable skill on the part of the operator to release the repeating key at the proper time, especially for tabular work where the 35 items are to be printed in vertical columns with considerable space between them.

The present invention is an improvement over the apparatus disclosed in said patent.

Briefly the principal feature of my invention resides in the addition of an arrangement 40 whereby the action of the repeating key is automatically interrupted at the proper time whether it be at the end of the line or at some intermediate point. Two 45 embodiments of this idea are illustrated. In one embodiment the operator holds the key depressed until a predetermined number of characters or punching operations have been made when a device controlled by the 50 movement of some part of the mechanism, as the em rack for example, stops further repetition, the operator then releases the repeating key and proceeds in the normal manner. This action may take place one or 55 more times for each line of the final printed

page. In the other embodiment the operator depresses the repeating key which is immediately locked in that position by suitable means and remains so until the device controlled by the em rack or equivalent device 60 releases it. From the view point of the operator, the difference between the two embodiments resides in the fact, that in one case he or she must depress and hold the repeating key until the necessary punching 65 operations have been made when the machine stops, while in the other case it is only necessary to depress the key and remove the finger, after which the operations are repeated without his or her assistance, until the proper number of operations have been made when the machine stops and the key is returned to its normal position.

Other novel features of my invention will be pointed out hereinafter.

In the accompanying drawings which are illustrative of my invention, Figure 1 is a perspective view of a part of a Lanston key board fitted with my repeating key and automatic stop; Figs. 2, 3 and 4 are detail views of the actuating and stopping mechanism; Fig. 5 is a plan view of a device to fasten the flexible cord of repeater key mechanism to the rock-shaft rods; Fig. 6 is a sectional view of the valve controlling the 80 ribbon feeding mechanism; Fig. 7 is a detail view in front elevation of the em rack and stop mechanism; Fig. 8 is a plan view of the key banks; Fig. 9 is a sectional view of the em rack and stop bar; Fig. 10 is a detail 85 view of the means for temporarily locking the repeater key in its depressed position, and Fig. 11 is a perspective view of the stop bar arranged to coöperate with the locking means of Fig. 10.

In order that my invention may be understood and its relation to previously existing constructions appreciated, it is necessary to briefly describe the latter; 11 indicates one of the ordinary keys which, when depressed by the operator, moves a bar having projections on the under side which in turn moves the rods 12 mounted on the rock-shafts 13. Each of these rods when pushed opens a valve 14 to admit compressed air to 100 the cylinder of the motor 15. The piston in the cylinder moves upwardly carrying with it the lever 16, bar 17 and punch 18, the latter making holes in the paper ribbon 19. The punches generally operate in pairs 110

through the action of the rods, and the air pressure closes the valves when the key is released. In some cases, as for example with the quad key, it is common practice to omit the punch from one or more of the bars 17, because certain characteristics of the casting machine in which the ribbon is subsequently used, and in particular as regards the means for moving the matrix case, render it unnecessary to perforate the paper for this character. Each bar and lever 16, however, move up and down for each operation of its associated key and the ribbon 19 is advanced step-by-step between operations as in other cases, and hence the operation, except for the punch perforating the ribbon, is the same in all cases. The two motors and punch bars shown are typical illustrations of these devices of which a large number is provided for each machine.

To withdraw the punches and return them to their depressed positions and also to control the action of the ribbon feeding means, mechanism including a tension arm 20 is provided that is actuated by a fluid motor 21 comprising a piston and cylinder. This motor always tends to hold the punches and rods depressed but is overpowered by the motors 15 when the latter are active. Connected to the tension arm by a link is a lever 22 that assists in the operation of the so-called unit-rack slide.

23 indicates a lever that is connected to the usual stop mechanism for the unit-rack slide.

The paper ribbon is fed between two perforated die plates 24 by toothed wheels 25. The shaft for these wheels is provided with a ratchet wheel 26, and the latter is advanced step-by-step by the pawl 27. The pawl is actuated by a rod 28 whose lower end is connected to the vibrating lever 29, the latter being tilted first one way and then the other by the pistons 30 and 31. When the machine is at rest the left hand end of the lever is elevated and moves down and up for each punch stroke. The pistons are controlled by the two-way slide valve 32 which is actuated by an arm 33 having a cam slot 34, said arm being actuated by the spindle of the tension arm 20. In the slot is a roller mounted on the lever 35, the latter moving the valve 32 to admit air under one piston and at the same time exhaust it from the other as shown in Fig. 6. The mechanism so far described is old.

As in my said patent I utilize the mechanism which withdraws the punches and retracts the bars and specifically the vibrating lever 29 of the paper feeding mechanism to perform the work of actuating the valves 14 of motors 15 when the repeater key is depressed, but I do it in a different manner and attain new and advantageous results.

65 40 indicates a flexible connector which can

best be made of metal cord or chain. It is connected at one end to a pair of the valve rods 12 as in my prior patent but in a different manner. The rods 12 are connected to the rock-shafts by vertical pins 41. Between a pair of pins I slip a strip 42, Fig. 5, of rather thin metal having notched ends partially embracing the pins. These strips have holes 43 to receive the ends of the connectors. One end of each connector is first attached to the strip, then the assembler flexes said strip with his fingers and slips it between the pins. When released the notched ends of the strip hold the same in place. This greatly facilitates the securing of the connectors and rods and also materially reduces the labor of adjusting the connector to obtain the exact length desired. In connection with this, as well as other devices to be described later, it must be remembered that one of the very great features of my invention is that the apparatus can be applied to existing machines without rebuilding them. The connector passes around pulley 44 and up over the pulley 45, said pulleys being mounted on the frame of the machine. In my patent aforesaid the other end of the flexible connector is connected directly to the vibrating lever 29. This former arrangement is entirely satisfactory in so far as the work performed by it is concerned, but it is rather objectionable in some cases from the view-point of wear and tear to have the connector continually subjected to motion. I avoid this by the addition of a lever 46 which is normally stationary and whose fulcrum is, or may be, the same as that of the lever 29. By using the same fulcrum 47, Figs. 3 and 4, for both levers 29 and 46, extra parts and unnecessary work are avoided. The lever 46 may either be flexible in a plane perpendicular to its length or it can be loosely mounted on its fulcrum to permit its free end to be moved away from the lever 29 to disengage the parts, as will appear later. Carried by the auxiliary lever 46 is a pin 48 that projects into the vertical plane of vibration of the lever 29, but normally stands just below the region of said vibration and is, therefore, not affected. A spring 49 tends to hold the auxiliary lever down thereby keeping the flexible connector 40 sufficiently taut to prevent idle movement as well as preventing the lever 29 from acting on the pin.

When it is desired to "quad out" a line or a portion of a line for example the repeating key 50 is depressed and this acting through the push rod 51 and lever 52 puts 125 the member 53 and flexible connector 40 under sufficient tension to pull the rods 12 forward and open the valves 14, thereby admitting air to the motors 15 which cause them to actuate the levers 16 and co-operat- 130

ing parts. When pressure is first applied to the repeating key, the auxiliary lever is held down because the right hand end of the main lever 29 rests on its pin 48. The upward movement of the punches turns the tension arm 20 on its axis together with the arm 33, which shifts the valve 32 to the left, the latter admitting air under piston 31 by pipe 31^a and permitting it to escape from under piston 30 by pipe 30^a. When the right hand end of lever 29 rises it releases the pin 48 thereby releasing the tension on the connector 40 and valves 14 cut off the supply and release the air from under pistons 15 and the latter return to normal position. This movement is accompanied by a shifting of the valve 32 with the result that the left hand end of the main lever 29 rises and its right hand strikes the pin 48 which restores the tension to the connector 40 and the action is repeated until some further act stops it. Owing to the fact that one or more of the motors act in response to a movement of the repeating key, the feeding mechanism will advance the ribbon 19 between each two similar movements, and hence it makes no difference if a punch has been omitted from a punch bar, providing, of course, as heretofore explained in connection with the matrix case of the casting machine, a punch is unnecessary to the successful operation. Whether a punch is used or not the record is made. In the one case the ribbon is perforated and in the other case not.

I will next describe an arrangement whereby the automatic action of the repeating key can be arrested at any predetermined point or points, particularly with the idea of facilitating the work where parallel columns in the printed page are required.

The machine is provided with an em rack 55 extending across the front and carrying the usual pointer 56 traveling over the fixed scale plate 57. Just below the rack I mount a bar 58 on pivots 59, the latter can be made of screws and threaded into the frame of the machine, there being ample space for the purpose. This bar is held in the raised position by the spring 58^a and has one or more adjustable stops 60, each having a top with a right and a left hand beveled face. Carried by the em rack is a finger 61 which, when it strikes a stop, depresses the bar and raises the arm 62 forming a side extension. This arm when elevated, assuming the repeating key to be held depressed by the operator, moves the right hand end of the auxiliary lever 46 sidewise by an amount sufficient to pull the pin 48 out of the region of vibration of the main lever 29, the final result being to release the tension on the connector 40 as completely as though the repeating key had been released and the machine stops. The operator is then free to work the machine in the normal manner or

to again use a repeating key. The next key struck regardless of what it may be causes the em rack to drag the finger over the beveled top of the stop. This action is facilitated by the fact that once the auxiliary lever and its pin are freed from the influence of the main lever 29 they are free to move upwardly at the rear end. Subsequently they are returned to normal position by spring 49. The rear end of the arm 62 is made to form a beveled faced cam so as to assist in moving the rear end of the lever and its pin 48 out of the path of lever 29. A screw 63 enables the necessary fine adjustment to be made. I have described the adjusting screw as being mounted on the auxiliary lever, but it can be mounted on the arm 62.

Each stop on the front bar 58 is adjustable sidewise and also vertically and is held in place by a screw 64. In order to insure the proper setting of these stops and hence the accurate stopping of the machine, they may be provided with pointers 66 that project in front of the scale plate 57 for the purpose of comparison. By beveling the upper faces of the stops as shown, the em rack and finger 61 can be moved in either direction by the normal mechanism. In other words, aside from serving as a stopping means or disconnector for the repeater key, the bar and its stop have no effect. During the usual key-by-key operation the finger 61 will ride over the stops first depressing the bar 58 and then releasing it, the auxiliary lever arrangement permitting this to take place.

In Fig. 7 is shown in elevation the relation of certain parts when mounted in place on the machine. 55 indicates the em rack which is mounted to slide in the slotted member 67, Fig. 9, said rack being driven by the pinion 68 on the shaft 69 of the unit wheel 70. 55^a indicates a roller for holding the em rack down so that it will not be forced out of place when the finger 61 strikes a stop 60 on the bar 58. The pawl 71 serves to hold the wheel until certain machine operations have been completed. 72 indicates the so-called driving cylinder and rotates the shaft 69 through the usual means that need not be described. 73 is the stop for the em rack 55. Below the rack is the pivotally supported releasing bar 58 for the repeating key 50. Above the bar is the scale plate 57 which is common to the em rack pointer 56 and to the pointers 66 on the stops. As constructed the em rack pointer 56 and the finger 61 are made of one piece, said parts extending through small holes in the em rack and being united on the back by 66^a, Fig. 9, after the fashion of a hair pin. This has the advantage that the pointer 56 prevents the finger 61 from turning when it strikes a stop. The arrange-

ment is simple in the extreme and also avoids additional clamping means which would cost money to make and would be more or less in the way.

5 In Fig. 8 is shown an arrangement whereby two repeating keys 50 and 74, representing for example a quad and a leader, are located in the right and left hand key banks. Key 50 acts through the push rod 51 on lever 52, and key 74 through push rod 75 on the bell crank lever 76, the latter being connected by a link 77 to the lever 78. The levers are connected by flexible connectors 53 and 79 to the main connector 40, Fig. 1. 10 The levers are held in tension by the springs 80. Each lever has a stop 78^a to limit its movement. It will thus be seen that either repeating key may be used to control the auxiliary lever 46, Fig. 1. It is to be understood, of course, that where the keys represent different characters, as they nearly always would, two connectors 40 are provided which extend to different pairs of rods 12.

15 As described thus far it is necessary for the operator to hold the repeating key down so long as it is desired to repeat the same character. That is to say, until the finger 61 automatically causes the release of auxiliary lever 46. I will now describe a means whereby the act of depressing a repeating key in addition to starting the mechanism into automatic action will lock said key in its depressed position until released by the action of the finger 61, stop 60 and bar 58. 20 This is a feature of great importance when combined with a suitable stopping means for it saves work and mental strain on the operator. It also gives the operator time in which to perform other work or move his hand preparatory to striking a normal key. 25 As an illustration of this feature of my invention I have shown in Figs. 10 and 11 the bar 58 provided with a suitably guided arm 85 which extends in front of the levers 52 and 78. This arm is provided with two notches 86 and 87, the former occupying a position in front of a projection 88, Fig. 10, on the lever 52 and the latter a position in front of projection 89 on lever 78. The portions of the arm adjacent the notches have beveled faces 90 and 91 over which the projections 88 and 89 ride. These levers are connected by flexible connectors 53 and 79 to the auxiliary lever 46, or they may be connected to the main vibrating lever 29 as described in my previous patent aforesaid. 30 The levers 52 and 78 overlap to reduce the overall total length. They are held in the position shown by extension springs 93 of suitable strength, which are secured at one end to fixed supports on the machine frame and at the other ends to the levers. The lever 78 has a projection 78^a that extends below it and forms a stop. The other lever 35 is also provided with a similar stop.

When the operator depresses key 50 the push rod 51 turns the lever 52 against the tension of its spring until the projection 88 drops into the notch 86. This action suffices to put the connector 40 under the necessary tension to cause the automatic repetition of the punch rods controlled by the key as already described. In addition the wall of the notch holds the projection 88 and locks the lever 52 so that the operator can release 40 the key without stopping the automatic action. The punches will continue to make holes in the paper ribbon 19, Fig. 1, or the rods to move up and down until the finger 61 on the em rack 55 strikes a stop 60 and depressing the bar 58 moves the arm 85 and its notches a distance sufficient to release the projection 88 and the machine stops. The action is the same for the other repeating key 74 except that the projection 89 enters the notch 87 and is held until released by a downward movement of the bar 58. When the tension on the connector is removed by releasing either the lever 52 or 78 the spring 58^a, Fig. 2, returns the auxiliary lever to its normal position where the movements of the main lever 29 do not affect it.

45 The flexible connectors can be made of any suitable material but after considerable experimenting I have found the small chains used on pull-sockets for incandescent lamps to be the best, as they are not only very flexible but are exceedingly strong for their size and do not stretch.

50 The combination of my repeating key mechanism with stop mechanism actuated by some movable part of the machine, as the em rack for example, is of importance for various kinds of work but has its greatest value for tabular work where one, two or more columns are to appear on the printed page, the remainder being quadded out or filled with dots, dashes, or other characters. It saves the operator both mentally and physically and insures absolute alignment of the various items in the columns as I have demonstrated in practical work. I prefer to use the em rack as a device to actuate the stop mechanism because it is in plain view and enables my improvement to be applied to existing machines without rebuilding, thereby increasing its field of usefulness, but I do not wish to be understood as limiting myself thereto. Furthermore, the arrangement permits me 55 to use one scale plate for the em rack pointer and the adjustable stops.

55 The locking of the repeating key in its depressed position is desirable in all cases because it relieves the operator mentally and physically. It has its greatest utility of course for tabular work, or work requiring continued use of the leader, quad or dash character. By combining the stopping and locking mechanism in one structure, as in 60

Figs. 10 and 11, I simplify the mechanism as a whole, reduce the number of parts and am able to locate it where it is accessible.

I have described my improved arrangement as depending for its action on the auxiliary lever 46, and in some instances on the main lever 29, because either of these arrangements can be applied with the minimum amount of labor and expense. It is evident, however, that my invention is not necessarily limited thereto since other vibrating parts of the usual operating mechanism can be employed. This is particularly true where the improvement is being incorporated in a new design where one need not be bound by the limitations imposed by existing structures and where success or failure is not so completely determined by simplicity and the ease with which the improvement can be added. It is also evident that while I have described the connector between the valve means or controller for the motor and the mechanism moving in synchronism with the feeding of the ribbon as being flexible, my invention is not to be construed as being so limited unless so stated in the claims.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. In an apparatus of the character described, the combination of devices for making records on a ribbon, mechanism for actuating the devices and feeding the ribbon, a repeating key which, so long as it is held in a predetermined position, acts on the mechanism to cause it to actuate one of the devices successively, and means responsive to certain movements of the mechanism for interrupting the action of the key.

2. In an apparatus of the character described, the combination of devices for making records on a ribbon, mechanism for actuating the devices and feeding the ribbon, a repeating key which, when depressed, acts on the mechanism to cause it to successively actuate the same device, a means for disconnecting the key from the mechanism, and a device moving in synchronism with the ribbon for actuating the last named means.

3. In an apparatus of the character described, the combination of a means for making a record on a ribbon, means for actuating it, a controller for the actuating means, mechanism for returning the record making means between operations, a nor-

mally idle means organized to first transmit movement from the mechanism to the controller and then release it for automatic operation, a repeating key for putting the last named means into operation, and a device for interrupting the action of the key on the controller.

4. In an apparatus of the character described, the combination of a means for making a record on a ribbon, means for actuating it, a controller for the actuating means, mechanism for returning the record making means between operations, a device moved by the mechanism and acting on the controller in a manner to cause the means to successively act on the ribbon, and a means for interrupting the action of the device on the controller after a predetermined number of record making operations.

5. In an apparatus of the character described, the combination of a punch rod, a motor for actuating it, a controller for the motor, mechanism for retracting the punch rod and moving the ribbon between operations which includes a vibrating member, a connector receiving motion from the member and transmitting it to the controller, said connector being normally idle, a repeating key for putting the connector into service, and a device for interrupting the action of the key on the connector and controller.

6. In an apparatus of the character described, the combination of a punch for perforating a ribbon, a fluid motor for actuating it, a valve controlling the motor, mechanism for withdrawing the punch and moving the ribbon between punching operations, a device which is normally idle for transmitting movements of the mechanism to the valve, a repeating key for putting the device into operation, and a means for disconnecting the device and valve.

7. In an apparatus of the character described, the combination of a punch for perforating a ribbon, a fluid motor for actuating it, a valve controlling the motor, mechanism for withdrawing the punch and moving the ribbon between punching operations, a device which is normally idle for transmitting movements of the mechanism to the valve, a repeating key for putting the device into operation, a means for disconnecting the device and valve, and a device which advances step-by-step between punching operations for actuating the last named means.

8. In an apparatus of the character described, the combination of a punch rod, a motor for actuating it, a controller for the motor, mechanism for retracting the punch rod, an em rack which advances step-by-step with the punch rod operations, a device which is normally idle for transmitting movements of the mechanism to the controller, a repeating key for putting the de-

vice into operation, and a means actuated by the em rack for disconnecting the controller and device.

9. In an apparatus of the character described, the combination of a punch rod, a motor for actuating it, a controller for the motor, mechanism for retracting the punch rod and feeding the ribbon, an em rack which advances step-by-step with the punch rod operations, a device which is normally idle for transmitting movements of the mechanism to the controller, a repeating key for putting the device into operation, a movable bar that extends parallel with the em rack for disconnecting the controller and device, an adjustable stop on the bar, and a finger moved by the em rack which acts through the stop to depress the bar and disconnect the controller and device.

10. In an apparatus of the character described, the combination of a device for making records on a ribbon, a fluid pressure motor for actuating it, a valve for controlling the motor, feeding mechanism for the ribbon acting between operations of the device and which includes a vibrating element, a member which moves step-by-step between the motor operations, a normally inactive connection between the valve and the vibrating element, a repeating key for putting said connection into action, and means cooperating with said member for nullifying the action of the key on the connection.

11. In an apparatus of the character described, the combination of devices for making records on a ribbon, motors for actuating them, controlling valves for the motors, feeding mechanism for the ribbon, an em rack which moves step-by-step between motor operations, a pivoted bar that extends parallel with the rack, a finger moved by the rack for depressing the bar under predetermined conditions, a connector between the feeding mechanism and the valves, a repeating key for putting the connector into service, and means actuated by the bar for nullifying the effect of the key on the connector.

12. In an apparatus of the character described, the combination of a means for making a record on a ribbon, mechanism for retracting the means and feeding the ribbon between successive record making operations, a key for controlling the normal operation of the means, a repeating key which, when moved to a predetermined position, causes the means to operate automatically, and a means for interrupting the control of the repeating key on the means.

13. In an apparatus of the character described, the combination of a motor actuated means for making a record on a ribbon, mechanism for retracting the means and feeding the ribbon between successive record making operations, a key for control-

ling the normal operation of the means, a repeating key which, so long as it is depressed, causes the means to operate automatically, and a means acting after a predetermined number of operations of the motor actuated means to release the latter from the control of the repeating key.

14. In an apparatus of the character described, the combination of a means for making a record on a ribbon, a mechanism for restoring the means and feeding the ribbon, a repeating key which, when moved, causes the means to act continuously, a lock for holding the key in its operative position, and a means for releasing the lock after a predetermined number of records have been made.

15. In an apparatus of the character described, the combination of means for making a record on a ribbon, mechanism for retracting the means and feeding the ribbon between successive operations of the means, keys for causing the means to act in the normal manner, a repeating key which, so long as it is depressed, causes continuous operation of the means, a lock automatically acting to hold the repeating key depressed, and a means for releasing the lock after a predetermined number of operations of the means.

16. In an apparatus of the character described, the combination of a means for making a record on a ribbon, mechanism for retracting the means and feeding the ribbon between successive operations of the means, a repeating key which, when moved to a given position, causes the means to operate automatically, a lock which becomes effective by the key movement, an adjustable stopping means responding to movements of the record making means, and mechanism for disconnecting the lock and key.

17. In an apparatus of the character described, the combination of a means for making a record on a ribbon, a ribbon feeding mechanism, individual repeating keys which, when depressed, set the means into automatic operation, a lock that is common to said keys for holding them in their depressed positions, a bar for releasing the lock, and means movable step-by-step with the ribbon for actuating the bar.

18. In an apparatus of the character described, the combination of a motor actuated means for making a record on a ribbon, a ribbon feeding mechanism, an em rack, a repeating key means for causing the motor means to operate continuously, a bar located adjacent the rack, means for locking the key means in operative position, and a device actuated by the rack for moving the bar in a manner to release the locking means.

19. In an apparatus of the character described, the combination of a motor actuated means for making a record on a ribbon,

a ribbon feeding mechanism, an em rack, a repeating key means coöperating with the feeding mechanism to cause the motor means to operate continuously, a lock for holding

a vibrating lever, a rock-shaft, a rod supported on the rock-shaft by pins, and a strip 35 of flexible metal supported between the pins which is secured to the connector.

5 the key means in its active position, and a means actuated by the em rack for releasing the lock.

20. In an apparatus of the character described, the combination of a motor actuated means for making a record on a ribbon, a ribbon feeding mechanism which includes a vibrating lever, a controller for the motor, a connector which is normally idle for transmitting movements of the lever to the controller, a repeating key for putting the connector into action, a lock therefor, and a means for releasing the lock and stopping the apparatus.

21. In an apparatus of the character described, the combination of a motor actuated means for making a record on a ribbon, a ribbon feeding mechanism which includes a vibrating lever, a means which is normally idle for transmitting movements of the lever to the controller of the motor, a repeating key, a lever moved thereby and arranged to act on the connector, a lock for holding the lever in its operative position, and a stop means which releases the lock.

22. In an apparatus of the character described, the combination of a motor, a punch actuated thereby, a valve controlling the motor, a feeding mechanism which includes

23. In an apparatus of the character described, the combination of a motor actuated means for making a record on a ribbon, 40 a ribbon feeding mechanism, a repeating key coöperating with the mechanism to cause the motor means to operate continuously, a pivotally supported bar, a lost-motion connection between the key and mechanism, a 45 lock for the key carried by the bar, and a means for moving the bar to release the lock.

24. In an apparatus of the character described, the combination of a punch for perforating a ribbon, a motor for actuating it, a 50 controlling valve therefor, mechanism for withdrawing the punch and feeding the ribbon which includes a vibrating lever, an auxiliary lever moved by the vibrating lever under certain conditions, and a repeating key 55 means for moving the auxiliary lever to a position where it is acted upon by the vibrating lever to cause automatic action of the valve and motor.

In witness whereof, I have hereunto set my 60 hand this third day of February, 1914.

CHARLES E. BENHAM.
